THE NORRIS PETERS CO., PHOTO-LITHO., WASHINGTON, D. C.

UNITED STATES PATENT OFFICE.

FRANZ BURGER, OF FORT WAYNE, INDIANA, ASSIGNOR OF THREE-FOURTHS
TO HENRY M. WILLIAMS, OF FORT WAYNE, INDIANA.

HOT-AIR ENGINE OR POWER-GENERATOR.

SPECIFICATION forming part of Letters Patent No. 747,316, dated December 15, 1903.

Application filed February 15, 1901. Serial No. 47,474. (No model.)

To all whom it may concern:

Be it known that I, FRANZ BURGER, a citizen of the United States, residing at Fort Wayne, in the county of Allen and State of Indiana, **5** have invented certain new and useful Improvements in Hot-Air Engines or Power-Generators, of which the following is a specification.

My invention relates to high-pressure hot-air engines or power-generators; and it has for its object to improve this class of engines or power-generators; and to these ends my invention consists in the various features of construction and arrangement of parts having **15** the general mode of operation substantially as hereinafter more particularly set forth.

Referring to the accompanying drawings, wherein I have illustrated a preferred embodiment of my invention, Figure 1 is a horizontal sectional plan of the engine and generator. Fig. 2 is a side elevation, partly in vertical section, of the engine and generator. Fig. 3 is a horizontal section of the generator, showing more particularly the regulating-ring **25** and connections. Fig. 4 is a side view, partly in section, of the generator, showing the regulating-ring and mechanism for operating the same. Figs. 5 and 6 are part cross-sections of Figs. 3 and 4, showing the regulating-ring **30** in different positions; and Fig. 7 is a side view, partly in section, showing the eccentric and connections for operating the inlet-valve.

Among the principal objects of my present invention one is to provide a hot-air engine **35** or power-generator of this particular class in which the air can be used at a relatively high temperature and pressure and higher than has been practicable up to the present time. Another object is to avoid the loss of power **40** resulting from the ordinary methods of utilizing the heat energy of fuel in hot-air engines and, further, to provide a power-generator which is capable of containing a large amount of fuel at one time, so that the engine **45** is enabled to run continuously for a relatively long period of time without the necessity of being recharged or furnished with a fresh supply of fuel. These objects thus generally stated, and others which will appear **50** from the description hereinafter, are attained by the use of an improved generator or engine

embodiment the general features of construction and having the general mode of operation substantially as hereinafter described.

Upon a suitable base A are mounted two **55** cylinders, one being the power-cylinder B and the other the air-compressing cylinder C. The power-cylinder B is provided with a working piston D, to which is attached the connecting-rod E, mounted on the crank-shaft **60** F, which is arranged and supported in the pillow-blocks G, connected with the base A, and this crank-shaft is connected to or provided with suitable means for supplying power, as a fly-wheel or belt wheel or pulley. **65** Connected with the crank-shaft and driven thereby is some suitable means of operating the piston K of the air-compressing cylinder C, and in the present instance I have shown a connecting-rod J, attached to the piston K **70** and to a disk crank H on the crank-shaft. The crank-pin H' of this disk crank is preferably arranged in such relation that it is about ninety degrees behind the power crank-pin F', although the exact relation of these **75** two cranks is not material to my invention.

It is of course desirable in an engine of this character to keep the cylinders cool, and the cylinders B and C in the present instance are surrounded by water-jackets L L', L' being common to both cylinders, and these jackets may be supplied with water or other liquid in any of the ordinary ways well understood by those skilled in the art and not shown herein. **85**

The power-cylinder B is in the present instance provided with an extension M, which extends beyond the working point of the piston D and is larger in diameter than the innerdiameter of the power-cylinder. This extension is provided with some heat resisting and retaining material, and in the present instance it is fitted with a lining or bushing N, of plumbago. The piston D is also provided with an extension in the form of a piston O, **95** working within the lining or bushing in the extension M of the power-cylinder, and this extended piston is also made of some heat resisting and retaining material, as plumbago, and it is attached so as to move with the piston D, and it may be attached in any suitable manner, as by the rod or bolt O'. The **100**

outer end of the extension M is also preferably provided with a similar lining or bushing, as the plumbago ring Q, which ring has a central opening R, corresponding with the 5 inlet-opening in the cylinder-head P.

Connected to the cylinder-head P is a valve-casing S for the admission-valve T, and connected to the casing S is a supply-pipe U, which may be provided with a suitable cut-off valve V and which is connected to the generator W.

The air-compressing cylinder C of the air-pump may be variously constructed; but, as shown, it is provided with a head X, to which 15 is attached a valve-casing 1, having in this instance a partition 2, and in one part of the casing is placed a suction-valve 3, connected with the air-inlet portion of the valve, and in the other a pressure-valve 4, through which 20 the compressed air from the cylinder C passes and thence flows through the pipe 5 to the generator W.

The generator W may be variously constructed; but, as before intimated, in order to 25 attain the objects of my invention it is desirable to provide a generator which is capable of holding a large amount of fuel and which shall utilize the heat to the best advantage and which shall be practically self-regulating 30 or automatic in its operation, and in the present instance I have shown the generator as composed of two shells, one within the other and with an annular space between them, the ends of the cylinders being closed by suitable 35 heads. Thus in the present instance there is an annular space 6 between the inner shell 7^a and the outer shell 7, and this space is divided about midway of the generator, the outer shell 7 being enlarged, so as to form an 40 annular space, and this may be accomplished by means of an annular casing 9, as shown. Mounted in this enlarged casing and extending from the inner casing to the outer is a ring 8, having in its face a number of perforations, as 14, and the inner shell 7^a is also 45 provided with a number of perforations, as 13, above the plane of the perforated ring 8. Some suitable means is provided for controlling these perforations and the passage of air 50 therethrough, and in the present instance I have shown an angle-shaped ring 10, provided with a number of perforations 11, which may register with the perforations 13 in the inner shell 7^a, and is also provided with a number 55 of perforations 12, which may register with the perforations 14 in the stationary partition or perforated ring 8. The number of perforations 14 in the partition-ring 8 is in the present instance double the number of those in 60 the movable ring 10, the purpose of which will appear later.

The inner shell 7^a of the generator is preferably protected from being burned or injured by the high temperatures produced 65 therein, and in the present instance I have shown it as provided with a lining 7^b, of fire-brick or similar refractory material, and I

preferably extend this lining throughout the inner body and top portions of the inner shell of the generator. Mounted in the generator is a suitable grate 15, and below this in the shell are the perforations 16, communicating with the inner space 6 between the two shells, and connected with the ash-pit below the grate is an ash-door 17, which 70 while it may be of any suitable construction is held air-tight against the generator—in the present instance by a screw 18 in the stirrup 19. The top of the generator is provided with a charging-door, as 22, and this is held 80 by a stirrup 20 and screw 21.

The ring 10 acts as a regulator or controller for the compressed air in the space 6, and the admission of this air into the generator is controlled by this ring, and it may be 85 admitted above the fuel in the generator or below it, or both, and the ring 10 may be operated by hand or other suitable means; but I preferably provide automatic means for accomplishing this result. In the present 90 instance I have shown a portion of the edge of the ring formed into a rack 23, with which engages a pinion 24, mounted on a shaft 25, supported in a bearing or bushing 26 and having on its outer end a pinion 27, 95 which meshes with a rack 28, connected in the present instance at its lower end to the piston 29, working in a cylinder 30. The upper end of the cylinder 30 is closed, as by a screw-cap 31, and inside of the cylinder 100 between the upper portion of the piston and cap is placed a spring, (shown as a spiral spring 32,) which tends to force the piston down in the cylinder. The lower portion of the cylinder in the present instance is fastened to a bracket 33, which becomes a cylinder-head and into which enters a pipe 34, the other end of which is connected with the annular space 6 above the regulating-ring. It will thus be seen that the position of the 105 piston 29 is automatically controlled by the pressure of the air in the air-space 6, and the piston is moved up under such pressure and against the pressure of the spring 32, so that the ring or regulating device is automatically 110 controlled thereby.

The air-inlet valve of the power-cylinder B may be variously controlled; but I have shown a forked lever 35, located within the valve-casing S, which is connected with a 115 lever 36 outside the valve-casing, and this lever in the present instance is connected, by means of a ball-and-socket joint 37, with an eccentric-rod 38. To operate this rod, there is an eccentric 39 mounted on the crank-shaft F, and embracing the eccentric 39 is a strap 40, having a tailpiece provided with a cylindrical horizontal boring 41, in which is mounted a spring 42 and which receives the collar 43 of the rod 38, and the boring is 120 closed by a cap 44, having a central opening, through which the rod 38 passes. The eccentric is provided with an extending arm 45, which in the present instance is pivoted to

one of the spokes of the fly-wheel 46, mounted on the shaft F, adjacent to the eccentric. The eccentric is also provided with an elongated boring 47, through which the crank-shaft passes and which allows the changing of the stroke of the eccentric, and this is accomplished by a lever 49, having a fulcrum on one of the spokes of the wheel 46, one end of which lever is provided with a link 50, attached to a lug 51, on the side of the eccentric 39, while the other end of the lever is provided with an adjustable weight 48, and the lever is also under the tension of a spring 52, tending to counteract the centrifugal force of the weight on the lever. It is evident that as the crank-shaft revolves, and with it the fly-wheel, the governing-weight 48 will tend to fly outward by centrifugal force, and this is counteracted by the spring 52, and between these two forces the lever 49 is controlled and moves the eccentric so as to bring the crank-shaft F in different positions or relations to the bearing-surfaces of the boring 47.

The power-cylinder is provided with an exhaust-valve of any suitable character, and in the present instance such valve 53 is shown as controlled by a crank 54, worked by a rod 55, bearing on a cam-roller 56 on a cam on the hub of the disk crank H.

Such being the general construction and arrangement of the parts, the operation of the engine will be largely understood from what has been stated heretofore.

In order to start the engine, the upper door 22 of the generator is opened and fuel is introduced into the interior of the generator, and when the combustion of this fuel has been started more fuel is introduced until the combustibles reach nearly to the central perforations 13, and the door 22 is tightly closed. Air is now let into the annular space 6 between the two shells of the generator, and in the case of a large engine this air may be introduced from a reservoir containing air under pressure; but in small engines a few revolutions of the fly-wheel will be sufficient to furnish the required amount of air under pressure to start the engine. Normally the regulating-ring will be in a position to permit the passage of the air through the openings 12, so that it passes down under the grate, entering the ash-chamber through the perforations 16, and passes up through the fuel and is heated. This of course causes an increased combustion and heats the air to a relatively high temperature, and it passes out of the generator W through the pipe U to the valve-casing S, and from there its passage into the power-cylinder B is controlled by the valve T, and it imparts motion to the piston D and thence passes through the connection with the crank-shaft F, and this in turn operates the piston K of the air-compressing cylinder or pump C, which maintains the supply of air in the generator. As the pressure of the air in the generator rises the regulating-ring 10 is moved by the pressure of the air in the cylinder 30,

which operates the piston 29 and through its connections moves the regulating-ring 10 so that the perforations 11 correspond to a greater or less extent with the perforations 13 in the generator, and the perforations 12 correspond to a greater or less extent with the perforations 14, and part of the air passes through the perforations 16 into the ash-chamber through the combustibles and part passes into the generator above the combustibles. A further adjustment of the ring 10 will operate to cut off the flow of all the air below the grate and cause all the air to pass through the perforations 13 into the generator above the combustibles, and it will be seen that by the mechanism described or other suitable mechanism the regulating-ring is automatically adjusted to direct more or less of the air through the combustibles or part through the combustibles and part above them or all of the air above the combustibles, and in the present instance this regulation depends upon the pressure of the air in the generator.

The valve T is operated by what may be termed the "shaft-governor," comprising the eccentric 39 and its connections, and according to the speed of rotation of the fly-wheel will the valve T be operated, so as to be open for a shorter or longer time and admit more or less of the compressed air into the cylinder B.

It will be seen that by the construction described when the valve T has seated to close the same the eccentric has not yet completed its stroke and that the collar 43 on the rod 38 will compress the spring 42 during the time the eccentric completes its stroke in one direction. When going out, the collar comes in contact with the cap 44, and thus the rod 38 is moved to open the valve. The time during which the valve is open depends, of course, upon the position of the eccentric with relation to the shaft F, and this is determined by the governor device described in a manner well understood.

With the construction above described I am enabled to operate the engine under a high temperature, and as an instance I may mention from 1,500° to 2,000° Fahrenheit, although, of course, the temperature in the power-cylinder will fall more or less from the temperature of the air in the generator. By constructing the power-cylinder B with an extension M and providing it with a bushing or heat resisting and retaining material air at a relatively high temperature can be used, and at the same time the cylinder can be maintained at a desirable temperature and comparatively little heat will reach the piston proper of the power-cylinder. Furthermore, as above intimated, it is desirable to provide a generator of a size that will receive a considerable amount of combustible material which will last quite a number of hours, so that the generator need not be opened to replenish the material for a considerable time,

and the arrangement shown meets this requirement. It is also evident that the forcing of the air through the fuel or combustible will result in some ashes or products of combustion being mixed with the compressed air; but I have found it unnecessary to attempt to separate the ashes and permit them to flow into the cylinder. They can be blown out through the exhaust-valve with the exhaust-air without serious detriment to the operation of the engine.

What I claim is—

1. In a hot-air engine, a heat-generator, comprising an inner and an outer shell having an annular space between them to receive the air to be heated and communicating with the interior of the inner shell through openings in two different planes, a perforated partition in the annular space between the planes of said openings, and means for controlling the flow of air through the perforations in said partition and the openings in the plane above it, substantially as set forth.
2. In a hot-air engine, a heat-generator, comprising an inner and an outer shell having an annular space between them to receive the air to be heated and communicating with the interior of the inner shell through openings in two different planes, a perforated partition in the annular space between the planes of said openings, and means automatically operated by pressure of air in said annular space for controlling the flow of air through the perforations in said partition and the openings in the plane above it, substantially as set forth.
3. In a hot-air engine, a heat-generator comprising an inner and an outer shell hav-

ing an annular space between them to receive the air to be heated, a perforated ring in the space between the shells, perforations in the inner shell above and below the fuel-space, and a valve seated on said ring controlling the flow of air from the space between the shells into the inner shell, substantially as described.

4. In a hot-air engine, a heat-generator comprising an inner and an outer shell having an annular space between them to receive the air to be heated, a perforated ring dividing the space between the shells, perforations in the inner shell below and above the fuel-space therein, a valve having openings controlling the perforations in the ring and in the inner shell, and means for automatically operating the valve, substantially as described.

5. In a hot-air engine, a heat-generator comprising an inner and an outer shell having an annular space between them to receive the air to be heated, a perforated ring dividing the space between the shells, an angle-shaped ring controlling the perforations through the ring and in the inner shell, a rack and pinion connected to operate the angle-shaped ring, and a cylinder and piston for operating the rack and pinion and connected to be operated by the variations of pressure in the inner shell, substantially as described.

In testimony whereof I have signed my name to this specification in the presence of two subscribing witnesses.

FRANZ BURGER.
